UNITED STATES PATENT OFFICE.

JOSEPH MARTIN CALLJU, OF CHICAGO, ILLINOIS.

CAR-COUPING.

No. 905,840.

Specification of Letters Patent.

Patented Dec. 8, 1908.

Application filed July 8, 1907. Serial No. 382,667.

To all whom it may concern:

Be it known that I, JOSEPH MARTIN CALLJU, citizen of the United States, residing at Chicago, in the county of Cook and State 5 of Illinois, have invented certain new and useful Improvements in Car-Couplers, of which the following is a specification.

This invention relates to car couplers of the type having a pivoted knuckle which 10 swings in the drawhead, and has for its object to provide an improved knuckle opener and lock, which can be operated conveniently from either side and which avoids the use of coupling pins and the like.

15 The invention is illustrated in the accompanying drawings, in which

Figure 1 is a plan view of a coupling head provided with the improvement. Fig. 2 is a horizontal sectional view thereof. Fig. 3 is a 20 vertical section on the line 3—3 of Fig. 2.

Referring specifically to the drawings, 6 indicates the coupling head and 7 the swinging knuckle, the tail piece 8 of which swings in a recess in the coupling head, as usual.

25 9 indicates a bar which is located in said recess and projects at one end through an opening in one side of the head. This bar is 30 slidable lengthwise across the head, on the floor or bottom of the recess in the head, and under the tail 8 of the knuckle, guides for its movement being formed by the front wall of the head and ribs 14 and 15 extending respectively across the floor and the top of said recess. The bar may be manipulated di- 35 rectly, or it may be connected to operating devices extending to the side of the car. It has in the upper side or edge thereof a recess or cut-out part as shown at 11, which when the bar is moved in one direction allows the

40 tail 8 to swing therethrough, but when the bar is moved in the other direction the solid part thereof moves to position in front of the tail of the knuckle, and so prevents said knuckle from swinging open. Said recess 11 45 produces also a shoulder 12 located on the opposite side of the knuckle from the body of the bar, so that said tail 8 swings in and out between the shoulders at the ends of the recess.

50 To unlock the coupling the bar 9 is pushed to the left, or into the head, until the end thereof adjacent the recess 11 passes from in front of the tail 8, at which time the shoulder 12 strikes against the rear or back side of the 55 tail 8 and swings the same outward, through

the recess, turning the knuckle on its pivot and opening the same.

The device will couple automatically, as when the coupling heads come together the knuckle is swung back, causing the tail 8 60 thereof to strike the shoulder 12 and slide the bar 9 to the right, bringing the solid portion thereof in front of the knuckle tail and forming the lock. This action is assisted or completed by means of an inclined projection 12^a 65 on the under side of the bar 9, which projection is properly positioned to slide down the beveled edge 13 at the end of the recess in the bottom part of the head 6. Thus, when the knuckle strikes the shoulder 12, in the 70 act of coupling, it pushes or throws the bar 9 to the right until the point or lower end of the incline 12^a passes over the edge 13 at the side of the head, after which the weight of the parts will cause the inclined projection 75 12^a to slide or settle down over said edge and complete the movement to advance the solid part of the bar in front of the tail of the knuckle. The part 12^a, after dropping over said edge, will also serve to prevent accidental disengagement of the lock, after being coupled. Sufficient space is left above the 80 top of the bar to permit lift or movement of said bar when it is moved to the left, for the purpose of unlocking the coupling and open- 85 ing the knuckle. The end of the tail 8 of the knuckle is turned or presented forwardly so as to bear directly behind the bar 9, to avoid any lateral pressure thereon which might tend to force the locking bar out of position. 90 As shown, the pressure of the knuckle binds the locking bar against the front side or wall of the recess in which it is held.

I claim:

1. In a car coupler, the combination with 95 a recessed head and swinging knuckle, of a lock bar slidable across under the tail of the knuckle in the recess in the head and having an upstanding projection engageable in front of the tail of the knuckle, to lock the same, 100 and clamped thereby against the front wall of the head, when closed.

2. In a car coupler, the combination with a head and pivoted knuckle, the head having a recess into which the tail of the knuckle 105 swings, said tail being offset at the inner end, of a locking bar slidable horizontally in the head and across the recess and engaging in front of the offset tail of the knuckle when locked.

3. In a car coupler, the combination of a head having a cross recess therein, a pivoted knuckle the tail of which swings into the recess, and a locking bar extending and slideable horizontally across the recess and under the tail of the knuckle, said bar having shoulders projecting upwardly on opposite sides of the tail of the knuckle and also having a projection inclined on the under side and adapted to slide out the end of the recess when the bar is shifted to locking position.

4. In a car coupler, the combination of a

recessed head having cross guides on the top and bottom of the recess, a swinging knuckle having an offset tail, and a lock bar slideable 15 in the guides across the recess and engageable in front of the tail of the knuckle, to lock the same when closed.

In testimony whereof I affix my signature, in presence of two witnesses.

JOSEPH MARTIN CALLJU.
